UNITED STATES PATENT OFFICE.

GILBERT A. PECAR, OF DETROIT, MICHIGAN.

DESIGN FOR A SIGNAL EXHIBITOR.

Application filed February 20, 1922. Serial No. 799. Term of patent 14 years.

To all whom it may concern:

Be it known that I, GILBERT A. PECAR, a citizen of the United States, residing at Detroit, in the county of Wayne and State of Michigan, have invented a new, original, and ornamental Design for a Signal Exhibitor, of which the following is a specification, reference being had to the accompanying drawing, forming part thereof.

Fig. 1, is a front elevation of an exhibitor, showing my new design;

Fig. 2 is an end elevation of the same.

I claim:—

The ornamental design for a signal exhibitor, as shown.

GILBERT A. PECAR.
